CONVEYER

Alfred L. Schlesinger, St. Louis, Mo.

Application February 26, 1951, Serial No. 212,715

5 Claims. (Cl. 198—140)

1

This invention relates to new and useful improvements in conveyors, and more particularly pertains to a conveyor of a type especially well adapted for elevating building materials during building construction.

The primary object of the present invention is to provide means of an exceptionally portable nature for elevating building materials to their point of use during the construction of a building, and which means may be readily adjusted for the increasing height of the building as the construction of the same progresses.

Another important object of the present invention is to provide a machine of this character which will require no special terrain or foundation for its installation, and which is readily adaptable to accommodate itself to the spacing of its base from the building and the slope of the ground upon which the same is positioned.

Still another important object of the present invention is to provide a machine of this character which will be extremely light in weight, and readily discribable so that the same may be easily transported between points of use.

Yet another important object of the present invention is to provide a machine of this character which will incorporate to a large extent equipment which is conventional in character and normally possessed by building contractors so as to lower the cost of the present invention, inasmuch as such equipment is capable of independent uses.

A meritorious feature of the present invention resides in the provision of a machine which incorporates conventional extensible ladder sections so as to lower the cost of the present invention, and to afford means whereby the machine may be readily adjusted for delivering building materials to different heights.

Another important feature of the present invention resides in the provision of an endless conveyor of the type which is readily discribable for reassembly in various lengths so as to accommodate for the adjustment of the extensible ladder sections.

Another important feature of the present invention resides in the fact that the ladder sections are rotatably mounted on the driving shaft of a conveyor so that the inclination of the ladder sections may be readily adjusted in accordance with the spacing of the lower end of the machine from the building.

Another important feature of the present invention resides in the provision of means for

2

rotatably mounting the ladder sections on the driving shaft, which will afford a certain amount of lateral movement of the ladder sections so that the same may be arranged in a vertical plane although the surface upon which the machine rests may be inclined.

Still another important feature of the present invention resides in the provision of means for securing the ladder sections to the building under construction, particularly in that such means are adapted to take full advantage of the hollow rung construction of the ladder for attachment thereto.

A further important feature of the present invention resides in the provision of guide strips that are attached to the rungs of the ladder to prevent the buckets of the conveyor striking the rungs.

Yet another feature of the present invention resides in the provision of bearings on the side walls of the hopper through which the horizontal drive shaft of the conveyor is journaled, whereby the angular position of the hopper with respect to the base may be adjusted to compensate for unevenness in the ground.

A still further important feature of the present invention resides in the entirely discribable construction employed in the machine throughout, whereby the same may be easily and readily disassembled or reassembled as desired, and whereby the ladder may be readily placed in condition for its conventional use.

These, together with various ancillary objects and features of the invention which will become apparent as the following description proceeds, are attained by the present invention, a preferred embodiment of which has been illustrated by way of example only in the accompanying drawings, wherein:

Figure 1 is a side elevational view of the present invention, showing the same installed for use;

Figure 2 is a front elevational view of the present invention as shown in Figure 1;

Figure 3 is an enlarged sectional detail view taken upon the plane of the section line 3—3 of Figure 1;

Figure 4 is another enlarged sectional detail view taken upon the plane of the section line 4—4 of Figure 1;

Figure 5 is an enlarged sectional view of the means provided for tensioning the endless conveyor;

Figure 6 is a perspective view of one of the clamping brackets provided for securing the ladders to the side of a building;

Figure 7 is a fragmentary perspective view of the manner in which the buckets are detachably connected to the endless chain;

Figure 8 is a top plan view of the lower portion of the machine, this view being taken upon the plane of the section line 8—8 of Figure 1;

Figure 9 is a vertical sectional view taken upon the plane of the section line 9—9 of Figure 8;

Figure 10 is a detail sectional view taken upon the plane of the section line 10—10 of Figure 2;

Figures 11 and 12 are perspective views of the elements forming the means by which the lower ends of the ladder rails are rotatably mounted upon the horizontal shaft;

Figure 13 is an enlarged sectional detail view of the means provided for securing the guide strips to the ladder rungs; and

Figure 14 is an enlarged sectional detail view of the bearing means provided for connecting the hopper to the horizontal shaft, this view being taken upon the plane of the section line 14—14 of Figure 8.

Reference is now made more specifically to the accompanying drawings, wherein like numerals designate similar parts throughout the various views, and in which the machine constituting the subject matter of the present invention is designated generally at 10.

Upon a base 12 is mounted a prime mover such as the internal combustion engine designated at 14, and a speed reducer 16. The output shaft of the prime mover 14 is operatively connected to the input shaft of the speed reducer 16 by means of suitable pulleys and drive belt designated generally at 18. Conventional clutch means, not shown, are provided for engaging and disengaging the driving connection between the prime mover 14 and the speed reducer 16, as will be understood, it being noted that such clutch means are provided with a suitable control handle 20 as shown in Figure 1.

Designated generally at 22 is a conventional extensible ladder including upper and lower sections 24 and 26, respectively, it being noted that the lower ladder section 26 includes brackets 28 slidably engaging the other section 24 so as to retain the ladder sections in parallelism, while the upper ladder section is provided with conventional hooks 30 for retaining the ladder sections in adjusted extended position.

While the ladder 22 may be of any suitable construction wherein the sections include side rails 32 connected by rungs 34, in the preferred construction the rails 32 and the rungs 34 are both of tubular metallic construction in the interests of strength and lightness in weight.

The output shaft 36 of the speed reducer 16 projects horizontally in spaced relation above the base 12, and is supported adjacent its free end by means of a bearing construction designated generally at 38. The bearing construction 38 comprises a pair of upstanding plates 40 and 42 which are spaced by spacers 44. The plates 40 and 42 are suitably secured to the base 12 as by fastening means 46, and extend upwardly in spaced relation above the spacers 44. The portions of the plates 40 and 42 projecting above the spacers 44 are provided with aligned openings through which the shaft 36 rotatably extends. For a purpose that will be seen presently, the plate 42 is preferably of two-piece construction with the upper portion of the same being detachably secured to the plate 40 and the spacers 44 by fastening bolts 48.

Means is provided for pivotally supporting the

ladder 22 upon the shaft 36 in such a manner that the ladder may be readily attached to or removed from the shaft 36. Inasmuch as identical means are provided for supporting each of the rails 32 of the lower ladder section upon the shaft 36, only one of such means will be described in detail. As best shown in Figures 10-12, a bearing block 50 is provided which has an opening 52 therethrough in which the shaft 36 is journaled. A connecting member 54 is provided which has a bifurcated lower end 56 in which is received the reduced upper end 58 of the block 50, and the furcations of the member 54 and the reduced upper end 58 of the block 50 are provided with aligned openings 60 and 62, respectively, through which a pivot pin 64 extends to pivotally connect the block 50 and the connecting member 54, it being noted that the pin 64 is perpendicular to the axis of the shaft 36. The upper portion of the connecting member 54 is shaped so as to be slidably received within the open lower end of a ladder rail 32, and the ladder rail 32 is secured to the member 54 by means of a pin 66 which extends through suitable apertures 68 in the rail 32 and the member 54. It will of course be understood that if the present invention is to utilize a ladder construction which does not include hollow ladder rails, the member 54 may be suitably attached to the side of the lower end of the ladder rail by any convenient means. It will thus be seen that the ladder 22 is supported on the shaft 36 and may be swung about the same as a pivot so that the vertical inclination of the ladder 22 may be readily adjusted. Furthermore, by virtue of the pivotal connection between the block 50 and the member 54, it will be appreciated that the ladder 22 is susceptible to a limited amount of angular movement about an axis perpendicular to the shaft 36.

It should be noted at this point that of the separate means provided for supporting each of the ladder rails, the block 50 of one of the same is received between the plates 40 and 42 of the bearing construction 38 so as to prevent movement thereof along the axis of the shaft 36, while the other block 50 is simply disposed on the shaft 36 intermediate the speed reducer and the bearing construction 38, it being apparent that the shaft 36 may be provided with adjustable collars for preventing axial movement thereof.

In order to properly space the ladder 22 from the building construction with which the invention is being used, and in order to prevent pivotal movement of the ladder 22 about either the shaft 36 or the pivot pin 64, means is provided on the ladder 22 for clamping the same to the building under construction, such as that indicated at 70 and shown in dotted outline. With attention directed particularly to Figures 1, 4 and 6, it will be seen that there has been provided a pair of clamps indicated generally at 72. Each of the clamps 72 includes an elongated bar 74 from which depends a fixed jaw 76 and an adjustable jaw 78. The jaw 78 is provided with an aperture 80 through which the bar 74 slidably extends, so that the adjustable jaw may be moved towards and away from the fixed jaw 76, and the jaw 78 is secured in adjusted position by means of a bolt extending therethrough which may be extended through a selected aperture of a series of apertures 82 provided in the bar 74. In the preferred construction, the movable or adjustable jaw 78 is provided with an adjustable clamping screw 84, whereby any suitable portion of

the building 10 may be securely engaged as indicated in Figure 1. The clamps 72 are connected to the ladder 22 by means of a rod 86 extended through one of the hollow ladder rungs 34 and links 88. One end of each of the links 88 is pivotally connected to the clamps 72 by means of a pivot bolt 90, while the other ends of the links are pivotally received on the opposite ends of the rod 86, the links 88 being retained upon the rod 86 by means of nuts 92 threaded upon the opposite ends of the rod 86. It will be evident that the rod 86 may be extended through any one of the rungs 34 desired, so as to allow for major adjustments in the vertical height of the clamps 72, while the pivotal movement of the links 88 afford minor adjustments in the vertical height of the clamps 72 so that the clamps 72 may be disposed at any vertical height desired.

A pair of collars or sleeves 94 are slidably positioned on the ladder rails adjacent the upper end of the upper ladder section, such sleeves 94 being provided with inverted U-shaped extensions 96 at their upper ends, and through the web portions of the U-shaped extensions 96 are threaded adjusting screws 98 which are adapted to bear upon the upper ends of the ladder rails so that the vertical position of the sleeves may be readily adjusted. The adjacent faces of the sleeves 94 are provided with opposed hollow bosses 100 which receive the opposite ends of a shaft 102. It will be understood that the shaft 102 may be journaled in the bosses 100 if desired, however, in the preferred construction the shaft 102 is fixed in the bosses 100 by means of set screws 104. A sprocket 106 is journaled on the shaft 102 intermediate its ends and is retained against axial movement on the shaft 102 by means of adjustable collars 108.

A further sprocket 110 is suitably keyed to an intermediate portion of the shaft 36, and an endless bucket-type conveyor is entrained over the sprockets 106 and 110, such conveyor being designated generally at 112.

The conveyor 112 comprises an endless chain 114 entrained over the sprockets 106 and 110, which chain 114 is provided at spaced intervals with conveyor buckets 116 as will be readily seen upon inspection of the drawings.

Attention is invited to Figure 7 for a disclosure of the means by which the buckets 116 are secured to the chain. Each of the buckets 116 is secured to the chain. Each of the buckets 116 is provided with a pair of clips 118 which include offset portions 120. A link 122 of the chain 114 is provided with oppositely extending fingers 124 which are received between the offset portions 120 of the clips 118 and the side wall of the bucket 116. In addition, the fingers 124 are provided with depressions 126 which receive corresponding depressed portions 128 in the offset portions 120 of the clips 118, so as to retain the clips in engagement with the chain. It will be understood, of course, that the clips 118 are formed of such a material having sufficient resilience to permit the fingers 124 to be withdrawn from engagement with the clips 118 so that the buckets may be detached from the chain.

In the preferred construction, not only are the buckets 116 detachable from the chain 114, but in addition the chain 114 is of such a construction that sections of the same may be removed so as to shorten the over-all length of the chain. Since readily discribable chains are well known in the art, a detailed description of the same is not deemed necessary here, it being sufficient to state that each of the links of the chain in-

clude loops 130 which may be twisted from engagement with the adjacent links.

Means is provided to prevent the buckets 116 striking the rungs 34, which means includes a pair of guide strips 132 carried by the rungs 34 and disposed between the rungs and the travel path of the buckets 116. The guide strips 132 are secured to the rungs 34 by means of spring clip constructions designated generally at 134. Attention is directed to Figure 13 for a detail view illustrating one of such spring clip constructions, wherein it will be seen that a U-shaped bracket 136 is secured by any suitable means to one side of the guide strip 132, with the web portion 136 being spaced from the strip 132. A generally C-shaped spring clip 138 is centrally secured to the bracket 136 as by a rivet or bolt 140, the clip 138 having concaved inturned ends 142 for engaging the opposite sides of a ladder rung 34. Preferably, the strips 132 are provided in sections which may be individually attached and removed from a ladder 22 so as to compensate for the adjusted extensions of the ladder 22.

A hopper construction is provided for feeding material to the buckets 116, such construction being designated generally at 144. The hopper construction 144 includes a chute portion having a bottom wall 146 and inclined side walls 148, and the construction 144 further includes a portion through which the buckets 116 are adapted to travel. This latter mentioned portion is disposed below the shaft 36 and is provided with an arcuate bottom wall 150 substantially concentric to the shaft 36 and side walls 152. It will be appreciated upon inspection of Figure 9 that material placed in the chute portion of the hopper will travel downwardly from the bottom wall 146 to the bottom wall 150 due to the inclination of the bottom wall 146. It will also be apparent that the buckets 116 will travel during their movement around the sprocket 110 closely adjacent the bottom wall 150 so as to become filled during their movement through the hopper. In order to prevent shovels or the like from striking the buckets 116, a guide plate 154 is provided in the hopper construction, the lower edge of the guide plate 154 being spaced above the bottom wall 150 so as to permit the movement of materials therebelow.

The hopper construction 144, like the ladder 22, is also pivotally connected to the shaft 36. The side walls 152 are cut away as at 156 to receive the shaft 36 therethrough. The side walls 152 are cut away as at 156 rather than being simply provided with openings therethrough in order to assure an easy means for separating the hopper construction from the shaft 36, as will be understood. A crescent-shaped member 158 (see Figure 14) is secured to the side walls 152 by means of fasteners 160, it being noted that the opening in the member 158 is in registry with the opening in the side wall 152 defined by the same being cut away as at 156. Bearings 162 are journaled on the shaft 36, and each of the bearings 162 are provided with enlarged, hollow axially extending portions 164 which embrace the crescent-shaped members 158, such extensions 164 being provided with set screws securing the same to the members 158. As shown in Figure 1, the hopper construction 144 is provided with a plurality of legs 166 for supporting the same, it being seen that by virtue of the pivotal connection of the construction 144 to the shaft

26, the same adapts itself to unevenness in the ground.

From the foregoing, the construction and operation of the device will be readily understood and further explanation is believed to be unnecessary. However, since numerous modifications and changes will readily occur to those skilled in the art, it is not desired to limit the invention to the exact construction shown and described, and accordingly all suitable modifications and equivalents may be resorted to, falling within the scope of the appended claims.

Having described the invention, what is claimed as new is:

1. In a conveyor assembly for converting a ladder having side rails and rungs into a conveyor frame, a bucket guide including a pair of elongated strips adapted to overlie the ladder rungs and extend parallel to the ladder side rails, brackets on the undersurface of said strips spaced from one another a distance substantially equal to the distance between ladder rungs, spring clips secured to said brackets and adapted to frictionally embrace the ladder rungs detachably supporting the strips thereon.

2. A conveyor for elevating building material comprising a base having a horizontal shaft mounted thereon, a ladder including side rails connected by rungs, means rotatably mounting the lower ends of the rails on the shaft, a second shaft rotatably mounted at the upper ends of the rails whereby a bucket conveyor may be entrained over the ladder by means of said shaft, an elongated guide strip extending between the upper and lower ends of the ladder and overlying the rungs thereof to prevent the conveyor buckets from striking the ladder rungs and detachable means securing the strip to said rungs.

3. A conveyor for elevating building material comprising a base having a horizontal shaft mounted thereon, a ladder including side rails connected by rungs, means rotatably mounting the lower ends of the rails on the shaft, a second shaft rotatably mounted at the upper ends of the rails whereby a bucket conveyor may be entrained over the ladder by means of said shaft, an elongated guide strip extending between the upper and lower ends of the ladder and overlying the rungs thereof to prevent the conveyor buckets from striking the ladder rungs and detachable means securing the strip to said rungs, said detachable means including brackets on the undersurface of said strip spaced from one another a distance substantially equal to the dis-

tance between ladder rungs and spring clips secured to said brackets frictionally embracing the ladder rungs.

4. In a conveyor assembly for converting a ladder having side rails and rungs into a conveyor frame, an endless chain having buckets thereon, means entraining the endless chain over the upper and lower ends of the ladder, a conveyor bucket guide including a pair of elongated strips overlying the ladder rungs throughout the length of the ladder and extending parallel to the ladder side rails, one rung of said chain being disposed between said guide strips so that the buckets ride against the guide strips.

5. A conveyor for elevating building material comprising a base having a horizontal shaft mounted thereon, a ladder including side rails connected by rungs, means rotatably mounting the lower ends of the rails on the shaft, a second shaft rotatably mounted at the upper ends of the rails whereby a bucket conveyor may be entrained over the ladder by means of said shaft, an elongated guide strip extending between the upper and lower ends of the ladder and overlying the rungs thereof to prevent the conveyor buckets from striking the ladder rungs and detachable means securing the strip to said rungs, said entraining means including a drive shaft, a supporting base mounting said drive shaft, the lower end of said ladder being pivotally attached to said drive shaft.
